UNITED STATES PATENT OFFICE.

CHARLES PFEIFFER, OF MILWAUKEE, WISCONSIN, ASSIGNOR TO THE ALLEN-BRADLEY COMPANY, OF MILWAUKEE, WISCONSIN, A CORPORATION OF WISCONSIN.

ELECTRICAL CONTACT.

1,220,679.

Specification of Letters Patent.

Patented Mar. 27, 1917.

Application filed November 19, 1913. Serial No. 801,796.

To all whom it may concern:

Be it known that I, CHARLES PFEIFFER, a resident of Milwaukee, in the county of Milwaukee and State of Wisconsin, have 5 invented certain new and useful Improvements in Electrical Contacts, of which the following is a full, clear, and exact description.

The invention relates to electrical contacts and their method of manufacture, and more particularly to that type of contact which includes a body or element of carbonaceous material, such as graphite.

Heretofore, it has been the practice to 15 electroplate the sides and one end of the carbonaceous element with an electrical conducting medium such as copper, to provide a suitable contact surface which is adapted to engage another contact or terminal. In 20 practice the carbonaceous conductors are raised to a high temperature and this causes the copper plate to become loosened, particularly when the thickness of the plate exceeds that used in the ordinary commercial plating, and this increased thickness is 25 desirable to withstand the mechanical stresses to which it is subjected in carrying the current desired. An example of this 30 type of contact and the manner of its use is set forth in Letters Patent No. 1,054,902, dated March 4, 1913.

In the use of graphite as an electrical conductor, some means is necessary to make a satisfactory and durable contact with the 35 metallic conductor or contact leading to or from the graphite conductor and the electro-plating of conducting medium onto the graphite was designed for this purpose.

I have found that carbonaceous material, 40 such as graphite, which is used in this type of contact, may be compressed and that by pressing the graphite element and the metallic container together, a more efficient contact results than that produced by electro-plating. By this compression operation, 45 an intimate contact between the graphite and the metallic conductor is obtained at considerable pressure over a relatively large area and furthermore, this intimate contact 50 is maintained despite the expansion and contraction of the two elements when they are subjected to varying and high temperature when in use.

A further objection to the electro-plating 55 was that the process was expensive and re-

quired a long time. By employing a separate container and placing the graphite body therein and compressing the two, a composite electrical contact of high efficiency is produced and the contact may be 60 quickly and cheaply manufactured.

Other advantages and objects of the invention will be manifest from the contact and method of making the same, hereinafter set forth.

The invention consists in the several novel features hereinafter set forth and more particularly defined by the claims at the conclusion hereof. 65

In the drawings: Figure 1 is a view, 70 showing the contact-member applied to a resistance device. Fig. 2 is a sectional view showing the contact-member in position in a die before compressing it. Fig. 3 is a sectional view showing the contact member 75 in position in a die after it has been compressed.

The electrical contact 10 is illustrated in Fig. 1 as applied to the end of a resistance device, which comprises a resistor 1 within 80 a containing chamber 2. The resistor 1 is made up of a series of resistance disks, which as a whole, make up the resistance element of the resistance unit. At the top of the series of resistance disks, a terminal 85 is provided and a graphite disk 14 is placed in contact with the top resistance disk. Upon the top of this disk 14, is mounted the contact 10, which is secured to a terminal plug 16 by a screw 17 and serves as 90 an electrical conductor between the terminal 16 and the disk 14, the contact being placed so that the bottom face of the metallic container abuts against the terminal 16. 95

The contact 10 comprises a body 11 of carbonaceous material, such as graphite, held within an intimately connected container 12 made of conducting material, such as copper. The graphite body or element 100 is provided with an aperture 13 through which the screw 17 is inserted to secure the contact 10 to the terminal 16. The aperture 13 is provided with a shoulder 15 against which the head of the screw 17 abuts. 105

In manufacturing the contact 10, a cylindrical cup or container 12 is formed of drawn copper or other suitable conducting metal, the walls of which are of the desired thickness, by pressing a piece of plate of 110

this material in suitable dies. The inside dimension of the cup is just sufficient to permit the easy insertion of the cylindrical graphite conductor 11 and the depth of the 5 cup 12 is such as to allow the graphite conductor-element to project out far enough from the upper edge of the cup, as shown at 20 to prevent any contact between the cup and the adjacent plate or conductor 14, 10 upon which the graphite disk is to bear.

The cup 12 and the cylindrical graphite conductor-element contained therein are then pressed into a cylindrical die 21 of such dimensions that the metallic cup is 15 pressed firmly around the graphite with sufficient force to reduce the diameter of both the metallic cup and the graphite conductor contained therein.

The result of this construction and manner of making it, is a metallic conductor surface which intimately contacts with the graphite conductor element; the metal and the graphite being constantly under a yielding pressure regardless of the relative 25 changes of dimensions of the metallic cup and the graphite conductor due to the different co-efficients of expansion of the materials when heated, or changes of dimension from other causes. The metallic element of 30 the contact can be made of any desired thickness, thereby affording any amount of mechanical strength and conductivity necessary.

The invention is not to be understood as 35 restricted to the details set forth, since these may be modified within the scope of the appended claims without departing from the spirit and scope of the invention.

Having thus described the invention, what 40 I claim as new and desire to secure by Letters Patent, is:

1. The method of making composite electrical contact members, consisting in connecting an elastic graphite element with a 45 metallic conductor element under sufficient resilient pressure of one element upon the other to compensate for differences in expansion and contraction due to the extreme changes in temperature to which such contact members are subjected and to maintain intimate pressure contact of a substantially constant degree between the elements notwithstanding such temperature changes.

2. The method of making composite electrical contact members, which consists in subjecting a body of elastic carbonaceous material to clamping pressure of a metallic container sufficient to reduce the volume of the portion of the carbonaceous material 55 which the container engages and develop sufficient elastic reactionary pressure to maintain the carbonaceous element and the container in intimate pressure contact under the varying temperature conditions to which 60 such contact members are subjected.

3. That improvement in making a composite electrical contact member which consists in uniting an elastic carbonaceous element with a metallic container by subjecting the container to sufficient pressure to distort 70 the container and densify the carbonaceous material therein sufficiently to produce an elastic reaction against the container under all service conditions of temperature variations.

4. An electrical contact composed of an elastic carbonaceous material and a conducting device adapted to maintain said material in a state of distortion under all service conditions of varying temperature, and notwithstanding differences in the co-efficient of expansion of the container as compared with 80 said material.

5. An electrical contact composed of an elastic carbonaceous material maintained in 85 a state of distortion by an electrical conductor medium, and adapted to maintain pressure contact with said medium under varying temperature conditions by resilient reaction.

6. An electrical contact composed of compressed carbonaceous material, and electrical conducting means adapted to maintain said material in a state of compression sufficient to reduce its volume under all conditions of 95 working temperature notwithstanding differences in the normal rate of thermal expansion and contraction of the carbonaceous material and the conducting means.

7. An electrical contact composed of compressed elastic graphite and means for maintaining said graphite in a state of compression under all service conditions of varying 100 temperature.

8. In an electrical contact, the combination of an elastic carbonaceous body and a metallic container, having walls against which the carbonaceous body resiliently expands, said body being sufficiently elastic to maintain an effective pressure upon the container under varying temperature conditions.

9. That improvement in making an electrical contact-member, which consists in placing a body of an elastic carbonaceous 115 material in a metallic container and subjecting the container and material to pressure so as to produce an intimate contact between the container and the carbonaceous material, the pressure being sufficient to densify the 120 body of carbonaceous material, and develop a permanent reactionary pressure of said material upon the container.

10. That improvement in making an electrical contact member, which consists in placing an elastic carbonaceous body or element in a separately formed metallic container of conducting material and subjecting the container to pressure to contract it 125 around the carbonaceous element.

11. An electrical contact comprising an elastic carbonaceous body, which is compressed and maintained in a state of compression by a surrounding member under varying temperature conditions.
12. An electrical contact comprising an elastic carbonaceous body, which is compressed and maintained in a state of compression by a surrounding metallic member, the diameter of which is relatively increased or diminished by changes in temperature.
13. In an electrical contact, the combination of an elastic cylindrical carbonaceous body and a metallic cup, said carbonaceous body having a portion thereof compressed in said cup and its volume materially reduced by the pressure of the walls of the cup.
14. In an electrical contact, the combination of a graphite body and a metallic container, said graphite body having a portion thereof inclosed by the container and held therein by expansive pressure of the inclosed portion against the walls of the container, said inclosed portion having a co-efficient of expansion, greater than that of the container.
15. In an electrical contact, the combination of a cylindrical graphite body and a metallic cup, said graphite body being compressed within said cup and maintained therein by expansive pressure against the walls of the cup.
